UNITED STATES PATENT OFFICE.

GEORGE C. WURSTER, OF RUTHERFORD, NEW JERSEY, ASSIGNOR TO WADE & BUTCHER CORPORATION, OF JERSEY CITY, NEW JERSEY, A CORPORATION OF NEW JERSEY.

FORGING MACHINE.

Application filed May 17, 1923. Serial No. 639,667.

This invention relates to a forging machine operative to automatically heat and shape metal blanks.

Heretofore, in forging operations, it has been customary to introduce blanks into a furnace by hand, leave them therein for a time sufficient in the judgment of the operator to properly heat them, and then transfer them by hand from said furnace to a rolling mill, drop hammer, or other shaping device. This practice does not insure even heating of the blanks, or subjection of the heated blanks to the action of the shaping device always in like condition. The main object of the present invention is the elimination of the human element in the transition of the blanks from a suitable source of supply, through heating means, and thence to shaping means and to a finished product, substituting for the manual operations heretofore employed mechanical operations performed by automatic machinery, thus reducing cost, maintaining uniformity of heating and shaping, and producing better products. Another object of the invention is the production of a machine wherein a succession of blanks is handled and each blank is subjected to the same degree of heat for the same length of time as all other blanks. Other objects are the production of a machine wherein the blanks are automatically transferred from a source of supply to heating means, from heating means to shaping means, or both. With these and other objects not specifically mentioned in view, the invention consists in certain constructions and combinations which will be hereinafter fully described and then specifically set forth in the claims hereunto appended.

In the accompanying drawings, which form a part of this specification and in which like characters of reference indicate the same or like parts, Fig. 1 is a side elevation of a machine constructed in accordance with the invention; Fig. 2 is a plan view of the machine shown in Fig. 1; Fig. 3 is a detail view taken on the line 3—3 in Fig. 2; Fig. 4 is a sectional view on an enlarged scale taken on the line 4—4 in Fig. 2; Fig. 5 is a cross-sectional view on a smaller scale of the structure shown in Fig. 4; Figs. 6, 7

and 8 are fragmentary and sectional detail views taken respectively on the lines 6—6, 7—7, and 8—8 in Fig. 5; and Fig. 9 is a fragmentary sectional detail view on a larger scale of a part of the structure shown in Fig. 5.

In carrying the invention into effect, there is provided means for heating blanks to be forged, means for shaping the heated blanks, and means for transferring the blanks from the heating means to the shaping means. In the best constructions, there is also provided a source of blank supply and means for transferring blanks therefrom to the heating means. In the best constructions also, the heating means operates to subject a succession of blanks to the same degree of heat for the same length of time in order that all the blanks will be in like condition when transferred from the heating means to the shaping means which will operate to progressively shape the heated blanks. The means above referred to may be widely varied in construction within the scope of the claims, for the particular machine selected to illustrate the invention is but one of many possible concrete embodiments of the same. The invention therefore is not to be restricted to the precise details of the structure shown and described.

Referring to the drawings, 10 indicates a foundation upon which the units constituting the machine are mounted. There is provided means for heating the blanks to be forged; and while this means may be otherwise constructed, as shown it includes a cylindrical furnace 11 having a heat resisting lining 12 of well known character. The furnace 11 is supported in elevated position by means of legs 13 rising from the foundation 10. The interior of the furnace is heated by gas entering the same tangentially through gas nozzles 14—14, the flow of gas through these nozzles being controlled by means of valves 15 of well known construction. The gas enters the furnace through the nozzles 14 under pressure, and a swirling movement of the gas is produced in the furnace as it burns so that all parts of the furnace are heated to the same degree of temperature.

squarely against the inner or bottom wall of the said socket. The operator then uses a hammer, striking the outer plug in the direction of the length of the axle whereby the wheel is jarred loose from the axle and the key thereof and may be quickly removed.

Having described the invention what is claimed is—

A device adapted to be used for removing a wheel from an axle upon which it is keyed comprising a body provided at its opposite ends with alined sockets of different sizes, and anvil plugs fitting in the sockets.

In testimony whereof I affix my signature.

CASH A. CLEMONS.

nism just described, a succession of blanks is transferred from the feed table 58 to the blank holders 18 as they successively come into position to receive the blanks.

Means are also provided for ejecting heated blanks from the furnace. While this means may be varied in construction, as shown, it includes a second plunger 66 which is longer than the plunger 60 and which works through the double-barreled member 28 and the single-barreled member 29 in the walls of the furnace, moving through the blank holder 18 which at the moment is in line with said members, and by its forward movement therethrough ejecting a heated blank from one blank holder 18 while the plunger 60 is loading a fresh blank into the adjacent blank holder 18, as clearly shown in Fig. 6. The rear end of the plunger 66 is secured to the crosshead 61 before referred to, and therefore movements of the two plungers 60 and 66 occur at the same time and are effected by the same means.

The plunger 66 serves to eject heated blanks from the furnace and, further, is a part of means for transferring heated blanks from the blank heating means to shaping means. This transferring means further includes a chute 67 into which a heated blank drops when ejected from the furnace, and down which it slides to blank shaping means. While other shaping means may be employed, as shown, a rolling mill 68 of well known construction is used for progressively shaping the heated blanks. The rolls of this mill are indicated by the dotted lines 69 and 70, which are co-incident with the pitch lines of a pair of superposed gears 71 which drive the shaping rolls in the usual manner. The lowermost roll is mounted on a shaft 72 which is driven by means of a gear 73 operated by a train of reducing gearing of the usual type and generally indicated by the reference character 74. Outside the gear 73, the shaft 72 carries a bevel gear 75 which is in mesh with another bevel gear 76 fast on the shaft 56 before referred to. By means of the intergeared relation of the rolling mill and of the mechanism for transferring the blanks, each part of the machine operates in timed relation with each other part. When the heated blank is to be shaped into a knife blade, for example, the rolls of the rolling mill are in the form of circular dies, and in such case it is necessary that the heated blank enter the bight of the mill rolls at the proper instant. To insure this, there is provided a plunger 77, the forward end of which works through a boss 78 formed on the bottom end of the chute 67. This plunger operates to push a blank which has slid down the chute 67 into the bight of the mill rolls at the proper time. The rear end of the plunger 77 is secured in

a head 78 connected by means of a link 79 to an arm 80 which is integral with the hub or fulcrum boss of the cam arm 44 before referred to. The plunger 77 therefore derives its movement from the cam 49 which also controls the movement of the ratchet mechanism for intermittently rotating the blank holders in the furnace. From the foregoing description, it will be understood that after quantities of blanks have been manually placed on the feed table, the machine automatically transfers a succession of blanks to the heating means wherein each blank is subjected to the same degree of heat for the same length of time and wherefrom the heated blanks are successively transferred to the rolling mill which progressively shapes them into the desired article in accordance with the contour of the mill roll dies. And in view of the foregoing, a detailed description of the operation of the device is deemed unnecessary to a full understanding of the invention, and is therefore omitted in the interest of brevity.

What is claimed is:

1. A forging machine comprising means for supporting a supply of blanks to be forged, means for heating the blanks for a definite period only, means for shaping the heated blanks, and controlling mechanism for said heating means operating at regular intervals to select and force blanks from said supporting means to said heating means and thence on completion of said period from said heating means to said shaping means. 90

2. A forging machine comprising means for supporting a supply of blanks to be forged, means for heating the blanks for a definite period only, means for shaping the heated blanks, and controlling mechanism for said heating means operating at regular intervals to select and force blanks from said supporting means to said heating means and thence on completion of said period from said heating means to said shaping means, 95

said supporting means including a table from which said mechanism selects and removes the blanks. 105

3. A forging machine comprising means for supporting a supply of blanks to be forged, means for heating the blanks for a definite period only, means for shaping the heated blanks, and controlling mechanism for said heating means operating at regular intervals to select and force blanks from said supporting means to said heating means and thence on completion of said period from said heating means to said shaping means, 110

said supporting means including an inclined table down which the blanks gravitate to be 120

successively removed by said mechanism. 125

4. A forging machine comprising means for supporting a supply of blanks to be forged, means for heating the blanks for a definite period only, means for shaping the 130

forged, means for heating the blanks for a definite period only, means for shaping the heated blanks, and controlling mechanism for said heating means operating at regular intervals to select and force blanks from said supporting means to said heating means and thence on completion of said period from said heating means to said shaping means, said mechanism including a plunger successively forcing blanks from said heating means.

14. A forging machine comprising means for supporting a supply of blanks to be forged, means for heating the blanks for a definite period only, means for shaping the heated blanks, and controlling mechanism for said heating means operating at regular intervals to select and force blanks from said supporting means to said heating means and thence on completion of said period from said heating means to said shaping means, said mechanism including a plunger successively forcing blanks into said shaping means.

15. A forging machine comprising means for supporting a supply of blanks to be forged, means for heating the blanks for a definite period only, means for shaping the heated blanks, and controlling mechanism for said heating means operating at regular intervals to select and force blanks from said supporting means to said heating means and thence on completion of said period from said heating means to said shaping means, said mechanism including a plunger successively forcing blanks from said heating means, another plunger successively forcing blanks into said shaping means, and a chute receiving blanks from the first plunger and delivering them to the second plunger.

16. A forging machine comprising means for supporting a supply of blanks to be forged, means for heating the blanks for a definite period only, means for shaping the heated blanks, and controlling mechanism for said heating means operating at regular intervals to select and force blanks from said supporting means to said heating means and thence on completion of said period from said heating means to said shaping means, said mechanism including a cam-actuated primary plunger successively forcing blanks to said heating means, a cam-actuated secondary plunger successively forcing blanks from said heating means, a chute receiving blanks from said secondary plunger, and a cam-actuated tertiary plunger successively forcing blanks from said chute to said shaping means.

17. A forging machine comprising means for supporting a supply of blanks to be forged, means for heating the blanks for a definite period only, means for shaping the heated blanks, and controlling mechanism for said heating means operating at regular

intervals to select and force blanks from said supporting means to said heating means and thence on completion of said period from said heating means to said shaping means, said shaping means including a rolling mill 70 receiving blanks from said mechanism.

18. In a forging machine, the combination with means for supporting a supply of blanks to be heated for forging, of means for heating the blanks for a definite period only, 75 and controlling mechanism for said heating means operating at regular intervals to select and force blanks from said supporting means to said heating means.

19. In a forging machine, the combination 80 with means for supporting a supply of blanks to be heated for forging, of means for heating the blanks for a definite period only, and controlling mechanism for said heating means operating at regular intervals to select and force blanks from said supporting 85 means to said heating means, said supporting means including a table from which said mechanism selects and removes the blanks.

20. In a forging machine, the combination 90 with means for supporting a supply of blanks to be heated for forging, of means for heating the blanks for a definite period only, and controlling mechanism for said heating means operating at regular intervals 95 to select and force blanks from said supporting means to said heating means, said supporting means including an inclined table down which the blanks gravitate to be successively removed by said mechanism. 100

21. In a forging machine, the combination with means for supporting a supply of blanks to be heated for forging, of means for heating the blanks for a definite period only, and controlling mechanism for said 105 heating means operating at regular intervals to select and force blanks from said supporting means to said heating means, said heating means including a furnace coating with said mechanism and in which blanks remain 110 during said period.

22. In a forging machine, the combination with means for supporting a supply of blanks to be heated for forging, of means for heating the blanks for a definite period 115 only, and controlling mechanism for said heating means operating at regular intervals to select and force blanks from said supporting means to said heating means, said heating means including a heated chamber, a 120 group of blank holders coating with said mechanism within said chamber, and a mount for said holders which permits them to expand freely.

23. In a forging machine, the combination 125 with means for supporting a supply of blanks to be heated for forging, of means for heating the blanks for a definite period only, and controlling mechanism for said heating means operating at regular intervals 130

squarely against the inner or bottom wall of the said socket. The operator then uses a hammer, striking the outer plug in the direction of the length of the axle whereby the wheel is jarred loose from the axle and the key thereof and may be quickly removed.

Having described the invention what is claimed is—

A device adapted to be used for removing a wheel from an axle upon which it is keyed comprising a body provided at its opposite ends with alined sockets of different sizes, and anvil plugs fitting in the sockets.

In testimony whereof I affix my signature.

CASH A. CLEMONS.

- mechanism for said heating means operating at regular intervals to force heated blanks on completion of said period from said heating means to said shaping means, 5 said heating means including a circular group of blank holders coacting with said mechanism, and means for intermittently rotating said group.
35. In a forging machine, the combination 19 with means for heating blanks to be forged for a definite period only, of means for shaping the heated blanks, and controlling mechanism for said heating means operating at regular intervals to force heated blanks on completion of said period from said heating means to said shaping means, 15 said heating means including a group of tubular blank holders in and out of which said mechanism loads and unloads blanks by moving them in the same direction.
36. In a forging machine, the combination 25 with means for heating blanks to be forged for a definite period only, of means for shaping the heated blanks, and controlling mechanism for said heating means operating at regular intervals to force heated blanks on completion of said period from said heating means to said shaping means, 30 said heating means including a circular group of transverse blank holders coacting with said mechanism, a shaft, spiders on said shaft, and connections between said spiders and said holders which permit the latter to expand freely.
37. In a forging machine, the combination 35 with means for heating blanks to be forged for a definite period only, of means for shaping the heated blanks, and controlling mechanism for said heating means operating at regular intervals to force heated blanks on completion of said period from said heating means to said shaping means, 40 said heating means including a cylindrical chamber, a plurality of gas nozzles opening tangentially into said chamber, a circular group of blank holders coacting with said mechanism within said chamber, and means for intermittently rotating said group.
38. In a forging machine, the combination 45 with means for heating blanks to be forged for a definite period only, of means for shaping the heated blanks, and controlling mechanism for said heating means operating at regular intervals to force heated blanks on completion of said period from said heating means to said shaping means, 50 said heating means including a circular group of blank holders coacting with said mechanism, and cam-actuated worm-gearing for intermittently rotating said group.
39. In a forging machine, the combination 55 with means for heating blanks to be forged for a definite period only, of means for shaping the heated blanks, and controlling mechanism for said heating means operating at regular intervals to force heated blanks on completion of said period from said heating means to said shaping means, 60 said heating means including a circular group of blank holders coacting with said mechanism, and means for intermittently rotating said group.
40. In a forging machine, the combination 65 with means for heating blanks to be forged for a definite period only, of means for shaping the heated blanks, and controlling mechanism for said heating means operating at regular intervals to force heated blanks on completion of said period from said heating means to said shaping means, 70 said heating means including a plunger forcing blanks on completion of said period from said heating means.
41. In a forging machine, the combination 75 with means for heating blanks to be forged for a definite period only, of means for shaping the heated blanks, and controlling mechanism for said heating means operating at regular intervals to force heated blanks on completion of said period from said heating means to said shaping means, 80 said mechanism including a plunger forcing blanks on completion of said period from said heating means.
42. In a forging machine, the combination 85 with means for heating blanks to be forged for a definite period only, of means for shaping the heated blanks, and controlling mechanism for said heating means operating at regular intervals to force heated blanks on completion of said period from said heating means to said shaping means, 90 said mechanism including a cam-actuated plunger successively forcing blanks on completion of said period from said heating means.
43. In a forging machine, the combination 95 with means for heating blanks to be forged for a definite period only, of means for shaping the heated blanks, and controlling mechanism for said heating means operating at regular intervals to force heated blanks on completion of said period from said heating means to said shaping means, 100 said mechanism including a plunger forcing blanks into said shaping means.
44. In a forging machine, the combination 105 with means for heating blanks to be forged for a definite period only, of means for shaping the heated blanks, and controlling mechanism for said heating means operating at regular intervals to force heated blanks on completion of said period from said heating means to said shaping means, 110 said mechanism including a cam-actuated plunger successively forcing blanks into said shaping means.
45. In a forging machine, the combination 115 with means for heating blanks to be forged for a definite period only, of means for shaping the heated blanks, and controlling mechanism for said heating means operating at regular intervals to force heated blanks on completion of said period from said heating means to said shaping means, 120 said mechanism including a plunger forcing blanks from said heating means, a chute receiving blanks from said plunger, and another plunger forcing blanks from said chute to said shaping means.
